TOY DOG

Florence Joan Schippert, Philadelphia, Pa.

Application June 12, 1952, Serial No. 20,147

Term of patent 7 years

(Cl. D34—2)

To all whom it may concern:

Be it known that I, Florence Joan Schippert, a citizen of the United States, residing in Philadelphia, Philadelphia County, State of Pennsylvania, have invented a new, original, and ornamental Design for a Toy Dog, of which the following is a specification, reference being had to the accompanying drawing forming a part thereof in which:

Figures 4 and 5 are rear and front elevational views respectively thereof.

I claim:

The ornamental design for a toy dog, as shown.

FLORENCE JOAN SCHIPPERT.
